8 Claims. (Cl. 273—126)

This invention relates to a control device for games played by movement of metallic game pieces along the playing surface of a gameboard for scoring determined according to the skill of the player in moving the game piece into a scoring location. The game piece moves into the scoring area according to the force and direction imparted to the game piece by the player. Pursuant to this invention means are provided for setting up a magnetic field across the playing surface of the gameboard as a barrier against playing such that as the game piece moves through said field and under the magnetic influence thereof it will be thereby retarded and deflected from its normal free course of movement in order to then prevent further normal use of or play on the device. The magnetic means are disposed, pursuant to the invention, away from the playing surface so that normal movement of the game piece may be attained, for a predetermined time, during continuance of a predetermined condition. They are automatically disposed so as to exert magnetic interference with the game pieces (susceptible to magnetic attraction), on occurrence of a different condition; they are moved away again so as not to interfere with normal movement of the game pieces, on termination of such different conditions.

Thus, for example, initially the magnet may be moved, pursuant to the invention, away from the playing surface on the player's depositing a coin. Then, after a lapse of time, or on attainment of a predetermined score, or on occurrence of some other condition, the magnet is moved into interfering relation by being automatically brought close to the playing surface. On occurrence of a different condition, such as deposit of another coin, the magnet is moved away from the playing surface. The foregoing and following description of conditions responsive to which the magnet is moved close to and away from the playing surface, and the specific switch, magnet and other means herein described, will enable those skilled in this art to practice the invention; in carrying out the invention other forms may be used, as will become apparent from the disclosure herein; such other forms, coming within the purview of the claims shall be deemed to be within the scope of the invention.

In the drawings:

Fig. 1 is a fragmentary, longitudinal sectional view, taken at line 1—1 of Fig. 4, of a play control device embodying the invention, shown applied to a game board,

Fig. 2 is an end elevational view thereof,

Fig. 3 is a side elevational, partly fragmentary view thereof,

Fig. 4 is a fragmentary, transverse sectional view taken at line 4—4 of Fig. 1, and

Fig. 5 is a schematic view showing a movable means which may be used in carrying out the invention, said means being shown in full lines in an intermediate position and in dotted lines after being moved to a final position.

As shown in the drawings, the invention is designed to control movement of a metallic member, of or includ-

ing a material susceptible to magnetic attraction, such as, for example, a shuffle-board puck 10 (Fig. 1) along the upper surface 11 of an elongated playboard 12. The invention is adapted for use in connection with games of any type wherein scoring is determined according to the skill of the player in moving a metallic game piece such as 10 along the upper surface 11 of, and toward a scoring area 13 of, an elongated playboard 12. The game piece 10 conventionally freely moves in a direction and for a distance determined by the skill of the player.

Pursuant to the invention, means are provided for deflecting the game piece from the path it would normally take. Said means are movable, pursuant to the invention, to two positions: In one position they exert an interfering action as above mentioned; in a second position they do not interfere.

The play control device comprises one or more magnets 14 (Figs. 1 and 4) secured to a rod 15 reciprocably disposed in a bearing 16, the latter being juxtaposed in the device spaced from the undersurface 17 of the play board 12 as, for example, by forming the bearing 16 unitarily with brackets 18 which in turn are secured to the undersurface of the play board as at 19 (Fig. 1). The magnets may be secured to the rod 15 directly or through a beam 20 or the like (Fig. 4). The rod 15 is connected as by linking means 21, 22 (Fig. 5) to a means for actuating said means and thereby the rod 15 (and magnets 14) also selectively to two positions. Said means may comprise the armature shaft 23 of a motor 24 in an arrangement such that on the rotation of the crank 22 for 180° the rod 15 will be moved to one position, for example, that shown in full lines in Fig. 4 for disposing the magnet 14 close to playing upper surface 11 of the game board 12 to exert effective magnetic attraction for game pieces 10 and interfering with the free normal movement thereof and, on movement of said link 22 another 180° will move the rod 15 and magnet 14 to the second position (shown in dotted lines in Figs. 1 and 4) at which the magnet 14 is moved away from the upper surface 11 of the playboard so as not to exert an appreciable magnetic attraction on a game piece 10.

In carrying out the invention as set forth above, suitable switch means may be provided for actuating the magnet reciprocating means selectively to the positions mentioned; said switch means may in turn be controlled by certain predictable conditions. For example, the motor may be energized to move the magnet away from the upper surface of the playboard when the player deposits a coin initially. To that end, a coin controlled switch (schematically indicated in Fig. 4 by the reference character 30) may be provided for closing the circuit through the cable 31 connected to the contact arm 32 which closes on the contact 33 connected by cable 34 with the contact arm 35 connected by cable 36 to the means for reciprocating the rod 15, such as the motor 24.

Thus, on deposit of a coin in the device 30 (which might be conveniently located at the player's end of the board 12) current will flow through the motor 24 so as to reciprocate the rod 15 for 180° from the full line Fig. 60 position to the dotted line position, correspondingly moving the magnet 14 away from the upper surface 11 of the playboard so as not to interfere with the free movement of the game pieces 10. Upon the occurrence of a second condition, such as, for example, upon the player's achieving a predetermined score (which might be displayed on a scoreboard or recorder 44 (Figs. 2 and 3)) or on the passage of time as reflected in a timing device 38 (which may in turn have been initially actuated on deposit of the coin) current will flow through the cable 39 from units 38 or 44 to the contact 40 with which the contact 41 will then be in engagement (the beam 20 which separates contacts 40 and 41 when in the raised—Fig. 4—posi-

tion being in the dotted line position, contacts 40, 41 will be closed—their operating normal position). Thus, current will flow through the cable 42 to the motor 24, energizing said motor, to reciprocate the rod 15 to the full line position shown in Fig. 4, whereupon the beam 20 will separate the contacts 40 and 41 and the motor will be cut off.

The specific switch and automatic actuating means above described are exemplary of other devices which will become apparent to those skilled in the art from a consideration of the foregoing description; such other devices shall be deemed within the scope and purview of the present invention. The playboard 12 may be provided with recesses 43 extending inwardly of the undersurface 17 thereof (Figs. 1 and 4) if desired to receive the magnets and enable them to move close to the playing surface 11 to enhance their magnetic deflecting action in terminating use of the board to prevent "free play."

Having thus described our invention, what we claim as new and desire to secure by Letters Patent is:

1. In a game having a playing surface for scoring, and in combination a timer, a control device comprising a magnet means disposed below the playing surface for deflecting a metallic game piece along the playing surface, toward a scoring area being of a material susceptible to magnetic attraction, means for conditioning the game for play including starting of the timer, means for disposing said magnetic means away from said playing surface so as not to exert any appreciable magnetic attraction on the metallic member, means responsive to detecting a score upon the scoring surface and means responsive to either the timer or to a predetermined score for disposing said magnet means toward the playing surface whereby said magnet means will exert a magnetic attraction on the metallic member effective to deflect it from its normal course of free movement toward the scoring area to thereby terminate the game.

2. In a control device for a game as set forth in claim 1, said playing surface comprising an elongated play board provided with a recess to receive said magnet and to thus dispose the same close to the playing surface of said play board on said movement of said magnet toward the surface.

3. In a play control device for a game as set forth in claim 1, said playing surface comprising one face of an elongated play board, the latter being provided with a recess on the surface thereof opposite said one face, said recess receiving said magnet and extending to a point close to said one surface, to allow the magnet to thus exert a magnetic attraction on the metallic game piece effective to deflect it from its normal course of free movement.

4. In a play control device for a game as set forth in claim 1, said means for so disposing the magnet including a bearing secured to the device beneath the playing surface and a rod secured to the magnet, movably arranged in said bearing for movement toward and away from the playing surface, and means to move said rod selec-

tively toward and away from the playing surface responsive to the selective occurrence of predetermined conditions.

5. In a play control device for a game as set forth in claim 1, said means to move the rod comprising link means connected to said rod, and means responsive to the occurrence of said conditions to move said link means, and to so move said rod.

6. In a play control device for a game as set forth in claim 1, said playing surface comprising an elongated play board provided with a recess transverse to the longitudinal axis, disposed on the underface thereof, and extended to a point close to the upper face of the play board, to receive said magnet.

15 7. A control device for use with a game having a playing surface and a timer played by posing a metallic member of material susceptible to magnetic attraction along a surface toward a scoring area according to the direction and distance of movement of said metallic member providing a barrier, said device comprising means for conditioning the game for play including starting of the timer, magnet means disposed below said playing surface for deflecting a metallic member along the playing surface, means for disposing said magnet means away from said playing surface so as not to exert any appreciable magnetic attraction on the metallic member, means responsive to the timer for disposing said magnet means toward the playing surface whereby said magnet means will exert a magnetic attraction on the metallic member effective to deflect it from its normal course of free movement toward the scoring area to thereby terminate the game.

8. A control device for use with a game having a playing surface and played by passing a metallic member of material susceptible to magnetic attraction along a surface toward a scoring area according to the direction and distance of movement of said metallic member providing a barrier, said device comprising means for conditioning the game for play, magnet means disposed below said playing surface for deflecting a metallic member along the playing surface, means for disposing said magnet means away from said playing surface so as not to exert any appreciable magnetic attraction on the metallic member, means responsive to detecting a score upon the scoring surface and means responsive to a predetermined score for disposing said magnet means toward the playing surface whereby said magnet means will exert a magnetic attraction on the metallic member effective to deflect it from its normal course of free movement toward the scoring area to thereby terminate the game.
